UNITED STATES PATENT OFFICE.

FRANZ A. FULLER, OF NEWARK, NEW JERSEY, ASSIGNOR TO THE J. E. MERGOTT CO., OF NEWARK, NEW JERSEY, A CORPORATION OF DELAWARE.

FASTENER.

Application filed June 30, 1923. Serial No. 648,692.

To all whom it may concern:

Be it known that I, FRANZ A. FULLER, a citizen of the United States, residing at Newark, in the county of Essex and State of New Jersey, have invented new and useful Improvements in Fasteners, of which the following is a specification.

One of the objects of the invention is to provide an efficient fastening device for holding two abutting elements, as for instance the cover and body of a trunk or like receptacle, in closed relation, the holding elements becoming automatically engaged by the application of moderate pressure.

Another purpose is to produce a holding device that can be positively locked, effectually preventing separation of the parts except by the use of a key suited to the structure.

A further aim is in the provision of a fastener composed of two normally separable elements, independently attached to the respective members of the receptacle at any preferred relative angle.

These aims, objects and purposes, together with others hereafter made manifest, as economic construction, ease of assembling and finishing, neatness of appearance, and general practical merit, are accomplished by the novel construction and combination of parts further on described and shown in the annexed drawings, forming part hereof, and in which:

Figure 1 is a general plan view of an embodiment of the fastener, illustrating its application and showing by broken lines various angular dispositions of the engaging elements.

Figure 2 is a side view of the same, indicating the use of a key in positively locking or releasing the elements.

Figure 3 is a partial plan, partial sectional view of the hinged hasp and its attaching member, the section being taken on line 3—3 of Fig. 4.

Figure 4 is a transverse sectional view of the same taken on line 4—4 of Fig. 3.

Figure 5 is a perspective view of the hasp and plate to which it is pivoted, the casing member being omitted.

Figure 6 is a perspective view showing in

detail the several parts composing the lock or hasp receiving portion of the structure, each in its relative position.

Figure 7 is a bottom plan view of the lock, parts being broken away to show the construction and assembly.

Figure 8 is a longitudinal sectional view of the lock taken on line 8—8 of Fig. 7.

Figure 9 is a transverse sectional view of the same taken on line 9—9 of Fig. 7.

Figure 10 is a perspective view of the sliding keeper plate in detail, reversed in position from that shown in Fig. 6.

In Figs. 1 and 2 of the drawings the numeral 15 designates a fragmentary portion of the main body of a receptacle and 16 the cover of the same, as for instance a trunk and its lid.

A casing 17, generally an elongated rectangle in shape at its base, is secured as by rivets 18, to the cover 16, this casing presenting a raised central portion 19 along one edge having a flat face blending into the base by sloping curves presenting a chamber 20 open at the top as illustrated.

A plate 21 is secured in the base by prongs 22 formed on the edge of the casing and indent as shown in Fig. 4 rigidly securing the parts together after assembling.

Said plate is sheared and bent to provide a central tongue portion 23 and a pair of opposed upstanding lugs 24 along its forward edge, these lugs being perforated to receive a straight hinge pin 25, on which is mounted a pair of bosses 26 fitting between the lugs and formed with a flat plate hasp 27 extending over and between them, tangentially from the peripheries of the bosses, in the plane of the surface of the casing element 19, when turned outwardly, presenting a level, substantially unbroken surface, readily amenable to polishing operations.

The lower side of the bridge 28, extending between the bosses 26, is recessed to provide space for a coiled torsion spring 29, encircling the pin 25, one end of the spring contacting against the under side of the hasp and the other end engaging a notch 30 in the edge of the tongue 23.

Thus the spring is entirely concealed, to-

gether with the hinge pin 25, the latter being held from longitudinal displacement by reason of its extending ends, which loosely fit between the opposed end walls of the chamber 20, rendering riveting or upsetting unnecessary and eliminating the distortion of parts usually consequent to such operations, beside the labor involved.

It is to be noted also that the spring 29 10 is free and untensioned when in the position shown in Fig. 5 but becomes operative when the hasp extends at a right angle to the casing, increasing in effect as the hasp is brought down into locking position as in Fig. 1, and furthermore, that no crevices appear at the joint between the hasp and casing to collect dirt and interfere with plating and polishing operations.

Fixed in the outer, rounded and reduced, 20 free end of the plate hasp 27 is a stud 31 having a semi-spherical head 32, partially separated from the body of the stud by an annular recess 33, this stud being rigidly held by riveting to extend from the under 25 side of the hasp.

The lock or hasp engaging portion of the structure comprises another oblong rectangular casing 35 held by corner rivets 36 to the body portion 15 of the receptacle, 30 this casing having flanged sides and ends blending by concave curves into a flat top plate 37.

Near one end of the casing is an opening 35 in which is rigidly secured a bushing 38 having a rounded, slightly extending upper end and projecting on the under side of the plate 37 to present stops 39 of somewhat more than a half circle for a purpose further on described, this bushing being suited to 40 receive the stud 31, the hasp element 27 resting on the extending end of the bushing when engaged.

Projecting from the edges of the end flanges of the casing 35 are prongs 40 bent over in assembling to hold in fixed relation the depressed ends 41 of a bottom plate 42 having upturned flanged sides 43, from which extend lugs 44 contacting with the interior of the casing, locating the plate centrally therein.

A central longitudinally raised strip 45 is formed with the plate 42, the same having a circular opening 46 in register with the bushing 38, into which the end 32 of the hasp stud may enter.

At the other end the strip 45 is sheared and the material bent to form a raised forwardly projecting prong 47 suited to enter one end of a coiled compression spring 48, guiding and acting as an abutment for the same.

The forward end of the spring 48 encircles a projection 49 formed at the end of a keeper slide 50, the main longitudinal portion of which is to one side of the center of

the casing, the other side presenting a recess 51.

Extending from the side edges of the slide, at the ends thereof, are lateral guide projections 52 adapted to slide between the flanged sides 43 of the bottom plate 42, and extending from the front of the slide is a keeper or detent element 53, bent slightly upward and notched to engage in the groove 33 of the hasp stud, the end of the keeper normally resting against the stops 39 of the bushing, so that in entering the hasp stud, the keeper will be pressed rearward until the curved end 32 of the stud has passed the end of the keeper, whereupon the spring 48 will press the keeper forward into locking engagement with the stud.

Interjacent the keeper slide and under side of the casing plate is a sliding cam plate 55, shaped at its outer end to conform with the profile of the keeper plate 50 and having pairs of narrow elongated slots 56 adjacent its side edges, the sliding cam plate being slightly narrower than the keeper plate and materially shorter.

At the center of the cam plate 55 is a round opening 57 and concentric with it, on its upper side, is a raised cam 58 highest at its center, the length of the cam being approximately 120 degrees.

The slots 56 in the cam plate 55 are in register with a single pair of elongated slots 59, formed through the casing top plate 37 and between these last named slots is an opening 60 having a cam-like profile, its opposite sides being different in radius and length as at 61 and 62, the longer radius, extending past the shorter to form a recess 63 and abutment 60'.

A hollow rectangular cap 64 is formed with a raised circular escutcheon 65 containing a key opening 66 having a downturned interior edge suited to receive the key 67, the same having opposed wards 68 and a tip 69.

The opposite side edges of the cap 64 have pairs of hook lugs 70 suited to pass through the casing plate slots 59 and plate slots 56, the extending hook portions of the lugs being thereafter bent outwardly, as at 71, holding the plate to the cap so that these elements move in unison.

A circular stem 72 extends upward into the cap 65, the stem having a transverse slot 73 in its upper portion adapted to receive the wards 68 of the key, while the tip 69 enters a corresponding depression in the stem at the bottom of the slot, it being understood that the stem is bored receptive of the body of the key.

Said stem is formed with an annular flange 74, below which is an integral lug 75 extending from the center to the periphery of the flange, and projecting from the lug, axially of the stem, is a pin 76 reach-

ing through the opening 57 in the cam plate 55, centering and aiding in conveying motion to it as the cap 64 is moved over the casing, and extending into the recess 51 of 5 the keeper slide 50, moving the same rearwardly when the cap is moved, thus freeing the keeper 53 from the head 32 and releasing the hasp.

Disposed between the flange 74 and under 10 side of the escutcheon 65, is a compression spring 77, encircling the stem 72, normally maintaining the flange pressed over the opening 60 and the pin 76 in operative relation with respect to the cam and keeper 15 plates.

It will now be seen that when the stem 72 is turned crosswise of the casing the lug 75 will pass over the highest point of the cam 58, compressing the spring 77 and permitting 20 the cap 64 to be moved rearwardly, freeing the hasp from its keeper.

Upon turning the stem by the key 67 to dispose the lug 75 lengthwise of the casing, its end will make contact with the trans- 25 verse edge or abutment 60' of the cam shaped opening, preventing movement of the cap and thus positively locking the hasp stud within the casing, but not preventing its entrance into the bushing 38 and becoming 30 automatically locked.

The shape of the cam opening 60 prevents turning the stem more than half a revolution and the effect of the spring 77 is to cause the stem to remain by friction in adjustment and not change therefrom by handling, jarring or the like until moved by the application of suitable force, this spring also assisting in positioning and maintaining the lug 75 in either of its adjusted positions longitudinally and with reference to the cam 58.

From the foregoing it will be understood that when the lug 75 is in the position shown in Figs. 7 and 8, the cap 64 and its 45 associated parts can be pressed towards the left of the structure as illustrated, moving the keeper 53 out of engagement with the grooved hasp stud, which will then rise due to the spring 29. When the lug is turned 50 oppositely its end abuts the element 60' preventing the slide moving, but the keeper plate 50 can be moved at all times to permit entrance of the hasp stud.

As the hasp stud 31 is circular it will obviously engage with the lock bushing 38 irrespective of the relative position of the casings, thus permitting them to be arranged at a right angle from either side or in register, as shown by the broken lines in Fig. 1, so that the same may be used either right or left handed without change in structure.

Although I have described my improvements with considerable detail and with respect to a particular form, I do not desire to be limited to the precise details, since

changes and modifications may be made without departing from the spirit and scope of my invention in its broadest sense.

Having thus described my invention, what I claim as new and desire to secure by Letters Patent, is:—

1. A fastener for containers having body and cover members comprising a casing attached to the cover member, a flat hasp hinged wholly within said casing, an annularly grooved stud fixed in said hasp, a casing attached to the body member, said casing having an opening near one end receptive of said stud, a spring actuated keeper 75 slideable in said second casing to engage the groove in the stud, a stop limiting the forward movement of said keeper, a slide cap on said second casing, said slide and keeper being connected to operate in unison, said slide being normally manually operable, and means for key locking said slide when in a forward position to said casing preventing motion thereof.

2. A fastener for containers having body and cover members comprising a casing attached to the cover member, a flat hasp hinged in said casing, an annularly grooved stud fixed in said hasp, a casing attached to the body member, said casing having an opening receptive of said stud, a spring 90 actuated keeper slideable in said second casing to engage the groove in the stud, a stop limiting the forward movement of said keeper, a slide cap on said second casing, said slide and keeper being connected to operate in unison, a cam plate intermediate 95 said casing and keeper, a stem in said cap operable by a key, a lug on the stem engageable with the cam carried by said plate, and a spring encircling said stem tensioned by lug and cam engagement, frictionally resisting movement of said slide cap.

3. A fastener comprising a casing having a level top plate and a bottom plate parallel therewith, said top plate having a circular opening near one end and a registering opening in the bottom plate, a keeper, spring impelled to normally extend into the space between the mentioned openings, a slide movable on said top plate, means associated with said slide to retract said keeper, key operated rotatable means to prevent or permit movement of said slide, said keeper being free at all times to be retracted, and a hinged element enterable through the opening in said top plate engageable by said keeper.

4. A fastener comprising a casing having a level top plate and a bottom plate parallel therewith, said top plate having a circular opening near one end and a registering opening in the bottom plate, a keeper, spring impelled to normally extend into the space between the mentioned openings, a slide 110 movable on said top plate, means associated 115 with said slide to retract said keeper, key operated rotatable means to prevent or permit movement of said slide, said keeper being free at all times to be retracted, and a hinged element enterable through the opening in said top plate engageable by said keeper.

with said slide to retract said keeper, key operated means to prevent movement of said slide, a cam plate intermediate said keeper and casing top plate, said cam plate controlling the movement of said key operated means, a tension means in said slide, a stop limiting the movement of said keeper, and a hinged element enterable through the

opening in said top plate engageable by said keeper.

This specification signed and witnessed this 29th day of June, 1923.
